Specification for Design.

Patented Aug. 7, 1917.

Application filed June 18, 1917. Serial No. 175,548. Term of patent 3½ years.

To all whom it may concern:

Be it known that I, FRANK L. WILMARTH, a citizen of the United States, residing at Central Falls, in the county of Providence and State of Rhode Island, have invented a certain new, original, and ornamental Design for an Emblem, of which the following is a specification.

In the drawings which form a part of this specification the figure is a front elevation of an emblem showing my new design.

I claim;

The ornamental design for an emblem as shown.

FRANK L. WILMARTH.
